(57) **CLAIM**

The ornamental design for an automotive engine cover, as shown and described.

DESCRIPTION

FIG. 1 is a front, left and top perspective view of an automotive engine cover.

FIG. 2 is a front view of the engine cover of FIG. 1.

FIG. 3 is a rear view of the engine cover of FIG. 1.

FIG. 4 is a right side view of the engine cover of FIG. 1.

FIG. 5 is a left side view of the engine cover of FIG. 1.

FIG. 6 is a top view of the engine cover of FIG. 1; and, FIG. 7 is a top, front, left and right perspective view of the engine cover of FIG. 1 shown in the environment in which the cover is typically mounted.

The dashed lines showing the various parts of the engine cover are for illustrative purposes only and form no part of the claimed design.
